US0D1106756S

(12) **United States Design Patent** (10) Patent No.: **US D1,106,756 S**
(45) Date of Patent: ** Dec. 23, 2025

(54) **BEVERAGE CONTAINER**

(71) Applicant: **Newtonoid Technologies, L.L.C.**,
Liberty, MO (US)

(72) Inventors: **Fielding B. Staton**, Liberty, MO (US);
Antonio Machado, Carrollton, MO (US)

(73) Assignee: **Newtonoid Technologies, L.L.C.**,
Liberty, MO (US)

(**) Term: **15 Years**

(21) Appl. No.: **29/873,255**

(22) Filed: **Mar. 28, 2023**

(51) LOC (15) Cl. **07-01**

(52) U.S. Cl.
